UNITED STATES PATENT OFFICE.

LESTER V. THOMAS, OF NACOGDOCHES, TEXAS.

CROSSING FOR RAILWAY-TRACKS.

1,331,831.

Specification of Letters Patent. Patented Feb. 24, 1920.

Application filed June 26, 1919. Serial No. 306,801.

To all whom it may concern:

Be it known that I, LESTER V. THOMAS, a citizen of the United States, residing at Nacogdoches, in the county of Nacogdoches, and State of Texas, have invented certain new and useful Improvements in Crossings for Railway-Tracks; and I do declare the following to be a full, clear, and exact description of the invention, such as will enable others skilled in the art to which it appertains to make and use the same.

This invention relates to crossings for railway tracks.

One object of this invention is to generally improve upon and simplify the construction of devices of this character by providing an improved pivotally mounted rail bridge which is out of the way of passing trains when in its open position, and improved abutments which keep the bridge alined with the rail, of which the abutments are elements.

A further object is to provide an improved device of this character which is very strong and durable.

Other objects and advantages may become apparent to persons who read the following details of description in connection with the accompanying drawings, in which:

Figure 1 is a top plan view illustrating two rails crossing at right angles to one another, one of said rails comprising my improved bridge.

Fig. 2 is an enlarged view showing the higher rail in transverse vertical section, the lower rail being shown in full lines, in side elevation.

Fig. 3 is a view partly in side elevation and partly in section.

Fig. 4 is a detail view partly in vertical section and partly in elevation, this view showing the interlocking relation of the crossed rails, and also showing my improved bridge in position over the lower one of the crossed rails.

Fig. 5 is a perspective view partly in section illustrating one of the interior surfaces which outline the gap in the higher rail, the section being taken at the middle of the gap.

Fig. 6 is a view similar to Fig. 1, but illustrating a modified form in which the rails cross one another diagonally.

Referring to these drawings in detail, in which similar reference characters correspond with similar parts throughout the several views, a railway rail 7 is formed with a

gap 8 which extends transversely through its base flange and terminates in its web. A higher rail 9 is formed with a gap 10 which extends transversely across the head of this rail and terminates in the web thereof. The gap 10 receives the head of the rail 7 in its intermediate portion, and this intermediate portion is sufficiently wide to provide clearance for the flanges of passing car wheels, such clearance being indicated at 11. Moreover, the gap 10 is formed with shelves 12 which are flush with the top of the rail 7. Between the shelves 12 and the upper surface of the rail 9, the latter is provided with arched surfaces 13 which terminate in shoulders 14, between which the ends of a bridge 15 are seated. The bridge 15 is provided with concaved lower surfaces 16 which fit over the convexed surfaces 13, so that lateral movement of the bridge is avoided. The lower surface of the bridge 15 is preferably plane, and the ends of this plane surface rest on the shelves 12, while the intermediate portion of the bridge may rest on the track 7, although the shelves 12 are sufficient to support the bridge independently of the track 7.

In order that the bridge 15 may be united with the rail 9 in such relation that it may be quickly and easily moved into and out of the gap 10, a link or lever 17 is pivotally connected to the bridge at 18 and pivotally connected to the track 9 at 19, on the side of the track 9 opposite to that on which the wheel flanges run. The link 17 is preferably of the angular shape shown in Fig. 3, so that its pivotal connection 19 is at a relatively low point on the rail 9, while its upper edge 20 is substantially level and flush with the top of the rail 9. Moreover, the ends of the normally level part of the link 17 may extend somewhat beyond the ends of the bridge 15, so that the car wheels ride upon these portions of the link slightly before they come to the bridge 15, to insure that the bridge is properly seated when the car wheels are thereon. This feature is useful because of the jarring and consequent bouncing up and down of the rails as the wheels roll therealong.

As the link 17 is pivoted to the bridge at 18, the latter may be disposed in a horizontal position on the top of the track 9 when the lever is swung back away from the gap 10, and therefore, the free end of the link 17 will not extend a sufficient distance above

the top of the track 9 to interfere with or be interfered with by trains which pass along the track 7.

Referring to the construction shown in Fig. 6, the bridge 15 and its connection with the rails 7' and 9' are substantially the same as previously described for the other figures in the drawings. The embodiment disclosed in Fig. 6 differs only from the previously described embodiment in the angles at which the rails are crossed.

In both embodiments of the invention, a bed-plate may be provided, the same being indicated at 20 in Fig. 4, and at 20' in Fig. 6, these bed plates being provided with shoulders 21 between which the base flanges of the rails are seated.

Although I have described this embodiment of my invention very specifically, it is not intended to limit this invention to these exact details of construction and arrangement of parts, but changes may be made within the scope of the inventive idea as described and claimed herein.

What I claim as my invention is:

1. A railway-rail having a gap extending transversely through its head and terminating in its web, said rail comprising upwardly arched surfaces terminating in shoulders at the upper part of the gap, and a bridge having concaved faces adapted to fit upon said arched surfaces while its ends are between said shoulders.

2. A railway-rail having a gap extending transversely through its head and terminating in its web, said rail comprising upwardly arched surfaces terminating in shoulders at the upper part of the gap, said

rail also comprising a horizontal plane surface at a lower level than said arched surfaces, and a bridge having concaved surfaces and a plane surface, said bridge being adapted to be seated in said gap so that its concaved surfaces fit upon said arched surfaces while its plane surface rests upon said horizontal plane surface.

3. The combination of a railway-rail having a gap extending transversely through its base and terminating in its web, a higher railway rail having a gap extending transversely through its head and terminating in its web, said railway rails being fitted together in transverse relation with their webs interlocking and the head of the first said rail in the gap of the said higher rail, and a removable bridge to close the gap of said higher rail.

4. The combination of a railway-rail having a gap extending transversely through its base and terminating in its web, a higher railway rail having a gap extending transversely through its head and terminating in its web, said railway rails being fitted together in transverse relation with their webs interlocking and the head of the first said rail in the gap of said higher rail, a removable bridge to close the gap of said higher rail, a bar pivotally connected to the higher rail and carrying said bridge, said bar having portions extending past the ends of the bridge and being substantially flush with the top of the head of the higher rail.

In testimony whereof I have hereunto set my hand.

LESTER V. THOMAS.
